UNITED STATES PATENT OFFICE

JOHN L. DRAKE AND LE ROY L. HANDY, OF TOLEDO, OHIO, ASSIGNEES TO LIBBEY-
OWENS-FORD GLASS COMPANY, OF TOLEDO, OHIO, A CORPORATION OF OHIO

SURFACING MACHINE

Application filed June 28, 1929. Serial No. 374,404.

The present invention relates to improvements in surfacing machines and particularly to grinding machines for treating sheets or plates of material such as glass and the like.

This invention is primarily adapted for, but not necessarily limited to, use in connection with grinding and smoothing plate glass in the so-called continuous system wherein the spindles of the grinding heads or runners are driven and the glass, mounted on cars or carriers, is carried beneath the runners of a series of machines.

An important object of the invention is the provision of improved means for connecting the grinding head or runner of the machine to its drive spindle whereby to permit movement of said runner relative to said spindle to compensate for any irregularities of the glass or unevenness on the glass surface.

Another object of the invention resides in the provision of an improved type of connection between the grinding head or runner of the machine and its spindle which will not only permit a limited and variable amount of universal rocking movement of said runner with respect to said spindle but which will further permit vertical movement of the grinding runner as a whole so that said runner will gradually lower relative to the spindle as the grinding lugs or projections thereon wear away.

A further object of the invention resides in the provision of novel means for indicating to the operator when the grinding lugs or projections on the grinding head or runner have become worn to a predetermined degree.

Still another object resides in the provision of improved means for effecting the raising and lowering of the grinding head or runner relative to the glass, together with means for limiting and automatically stopping the upward movement thereof.

Other objects and advantages of the invention will become more apparent during the course of the following description when taken in connection with the accompanying drawings.

In the drawings forming a part of this application and wherein like numerals are

employed to designate like parts throughout the same.

Fig. 1 is an elevation of a grinding machine, partially in section, and embodying the present invention.

Fig. 2 is a vertical sectional view through the grinding runner and the means for connecting the same to its spindle.

Fig. 3 is a section taken substantially on line 3—3 of Fig. 2.

Fig. 4 is a section taken substantially on line 4—4 of Fig. 3.

Fig. 5 is a section taken substantially on line 5—5 of Fig. 4.

Fig. 6 is a view similar to Fig. 4 but disclosing a slightly modified construction.

Fig. 7 is a section taken substantially on line 7—7 of Fig. 6, and

Figs. 8, 9 and 10 are diagrammatic views illustrating the electrically actuated means for limiting the upward movement of the grinding runner and automatically stopping the same.

As illustrated in Fig. 1, the glass sheets to be surfaced may be secured upon the tops of a plurality of tables 12 mounted upon wheels 13 riding on rails 14, said tables being driven in any suitable manner to carry the glass sheets beneath a plurality of grinding machines of the character to be herein-after described.

In the drawings, the letter A designates in its entirety a grinding machine constructed in accordance with the present invention and carried or mounted upon a supporting frame B. The frame B consists, briefly stated, of a hub 15 from which extend a plurality of substantially horizontal supporting arms 16, 17 and 18 mounted at their outer ends upon suitable supporting columns 19 and 20, said hub 15 being provided with an internal recess having a raised bearing portion 21 at substantially the center thereof.

The grinding machine A embodies a housing 22 mounted upon the hub 15 of the supporting frame B and through which passes the vertical drive spindle or shaft 23 journaled intermediate its ends within the bearing 21 and carrying at its lower end the grinding head or runner 24 which consists

of a main casting or base member 25 having secured to the bottom face thereof a plurality of metallic grinding lugs or projections 26. Slidably keyed to the drive spindle 23 and located within the recess in hub 15 of the supporting frame B is a worm gear 27 driven from the motor 28 through the motor shaft 29 and a worm (not shown) but which meshes with the worm gear 27. The motor 28, it will be noted, is mounted upon the supporting column 20 to one side of the machine.

The upper end of the drive spindle 23 carries a threaded sleeve 30 upon which is threaded the rotatable but non-slidable nut 31 carrying a worm gear 32 driven through suitable drive connections from a motor 33 supported upon the horizontal platform 34 carried by housing 22. Upon operation of motor 33 to effect rotation of worm gear 32 and nut 31, the sleeve 30 and consequently the drive spindle 23 will be threaded upwardly or downwardly through said nut dependent upon the direction of rotation thereof to effect either a raising or a lowering of the grinding head or runner 24.

An aim of the present invention is to provide novel and improved means for securing the grinding head or runner 24 to its spindle 23 in order to permit not only a limited and variable amount of rocking movement of said runner but also a bodily vertical movement thereof with respect to said spindle. To this end, there is mounted upon the base member 25 of grinding runner 24 centrally thereof, an annular housing 35 adapted to receive therein the lower end of the drive spindle 23. The annular housing 35 is secured to the runner by means of a plurality of bolts or the like 36 and is provided with a fixed top or cover plate 37. The lower end of the spindle 23 received within the housing 35 is formed with an enlarged annular head 38 through which extends the transverse pin 39 rotatably mounted therein. The pin 39 projects at its opposite ends beyond the head 38 and the projecting end portions 40 and 41 thereof are formed with opposite flat side faces 42 and 43. The projecting end portions 40 and 41 of pin 39 are loosely received within vertically extended openings 44 in bushings 45 fitted within diametrically opposite recesses 46 formed in the annular housing 35. It will be noted that the vertical extent of the openings 44 in bushings 45 is considerably greater than the vertical extent of the projecting end portions 40 and 41 of pin 39 so that while the ends of the pin do not have any rotative movement within the bushings, yet they are permitted to move vertically relative thereto. In other words, there is considerable clearance space between the projecting end portions of the pin 39 and the cover plate 37 of the annular housing 35.

With such a construction, and upon rotation of spindle 23, the runner 24 will be positively driven due to the engagement of the projecting end portions of pin 39 with the annular housing 35. Since the pin 39 is rotatably mounted within the head 38 of spindle 33 the runner 24 will be permitted to rock about the same and likewise the runner will also be permitted to rock in a direction at right angles with respect to its first rocking movement due to the vertical extent of the openings 44. The runner will also be permitted a certain amount of vertical bodily movement with respect to the spindle. The upper surface 47 of head 38 of spindle 23 is spherical and the undersurface 48 of the cover plate 37 is correspondingly shaped so that even when the runner is lowered to such a position that the cover plate will rest upon the head, the runner will still be permitted a certain amount of rocking movement.

This invention also embodies means for indicating to the operator when the grinding projections 26 on the grinding runner become worn to a predetermined degree or to the extent that they should be removed and new grinding projections substituted therefor. This indicating means includes the vertically disposed cooperating indicating members or pins 49 and 50 carried by the runner 24, the member 49 remaining stationary upon downward movement of said runner while the member 50 moves therewith. The cover plate 37 of housing 35 is provided at one point with a vertically thickened portion 51 having a recess in the undersurface thereof within which is fitted a cup member 52 having an opening in its bottom. The stationary member 49 projects downwardly through the cup member and engages the upper surface of the adjacent reduced end portion of the pin 39 and, as shown in Fig. 2, the end portion 40. Encircling the member 49 within cup 52 is a compression spring 53 bearing at its upper end against cover plate 37 and at its lower end against a collar or flange 54 on pin 49, said spring acting to normally urge the member 49 downwardly into engagement with the reduced end 40 of pin 39. The movable member 50 is threaded at its lower end within an opening in the cover plate 37 and the upper end thereof is turned inwardly as at 55 and positioned opposite the member 49. In practice, when the grinding projections 26 are new and the runner is properly lowered into contact with the glass, the spindle head 38 is lowered within housing 35 until the members 49 and 50 assume the positions with respect to one another as indicated by the full lines in Figs. 3 and 5. In other words, the lower edge of the in-turned portion 55 of member 50 should be substantially in line with the upper end of member 49. However, as the grinding projections become worn, the runner will be

gradually lowered and upon lowering of said runner the member 50 will be carried therewith while the member 49 will remain stationary. When the member 50 reaches the position indicated by the broken lines in Fig. 5 it will indicate to the operator that the grinding projections have become worn to the extent that they should be replaced. A boot 56 encircles the cover plate 37 and spindle 23 to prevent oil or abrasive material from passing downwardly around the spindle into housing 35 and a similar boot 57 is secured to and encircles the thickened portion 51 or cover plate 37 and member 49.

In Figs. 6 and 7 is disclosed a somewhat modified construction wherein the transverse pin 39 is eliminated and in its stead are provided the four pins 58, 59, 60 and 61. The pins 58 and 60 are threaded into the head 38 of spindle 23 at diametrically opposite points while the pins 59 and 61, which are positioned at right angles to the pins 58 and 60, are also threaded into the head at diametrically opposite points. The outer end of each pin 58 to 61 is rotatably received within a substantially square bushing 62 fitted within a recess 63 formed in the annular housing 35. Upon reference to Fig. 7, it will be seen that the vertical extent of the recess is considerably greater than that of the bushing so that while the bushing is prevented from rotating within the recess it is movable vertically therein. With such a construction, the runner will be permitted to rock in two different directions at substantially right angles to one another and will also be allowed a certain amount of vertical bodily movement. The runner can rock in one direction upon the pins 58 and 60 and in a direction at right angles thereto upon the pins 59 and 61. The improved indicating means above described can also be incorporated with this form of apparatus as shown in Fig. 7.

The present invention further embodies electrically operated means for not only raising and lowering the grinding runner with respect to the glass, but for also limiting the upward movement thereof and automatically stopping the same when it reaches a predetermined position. Thus, there is mounted upon the upper end of housing 22 of grinding machine A a casing 64 carrying a switch including the fixed and movable contacts 65 and 66 respectively (Fig. 8), the movable contact 66 being carried at the forward end of a lever 67 pivoted intermediate its end as at 68 and normally held in engagement with the fixed contact by means of the spring 69. The numeral 70 designates a second switch adapted to be positioned within convenient reach of the operator and having the three contacts 71, 72 and 73. The switch 70 also includes the contact fingers 74 and 75 adapted for engagement at any one time with any

two adjacent contacts 71, 72 and 73 and fixed to a shaft 76, said contact fingers being normally maintained in an open or neutral position as shown in Fig. 8 by a tension spring 77.

Leading from the fixed contact 65 is a wire 78 connected to the motor 33 while running from the movable contact 67 is a wire 79 connected with the contact 71 of switch 70. Secured to the contact 73 of switch 70 is a second wire 80 running to the motor 33 and wires 81 and 82 lead from the contact 72 of switch 70 and motor 33 respectively and are connected with the positive and negative main lines 83 and 84. Carried by the shaft 76 of switch 70 is a head or hand gripping portion 85 having an indicator 86 which is adapted to register, upon turning of said hand portion, with the words "Up" "Down" and "Off" written on the switch casing. Mounted above the lever 67 carrying the movable contact 66 is an arm 87 pivoted intermediate its ends as at 88 and carrying at its rear end a knock-out bolt or the like 89 adapted to engage the rear end of lever 67 and to swing the same about its pivot 68 to disengage the movable contact 66 from fixed contact 65.

In operation, during the grinding of the glass, the contact fingers 74 and 75 of switch 70 are held in the position indicated in Fig. 8 and out of contact with the contacts 71, 72 and 73 by the spring 77 so that this switch is open. At such time, the contacts 65 and 66 are held in engagement by spring 69 and the arm 87 assumes the position indicated in Fig. 9.

When it is desired to move the grinding runner 24 upwardly, the operator grasps the hand gripping portion 85 of switch 70 and rotates the same to move the indicator 86 opposite the word "Up" and upon such movement the contact fingers 74 and 75 will be moved to engage contacts 71 and 72 respectively and thus close the switch. The electric current will then enter through the positive main 83 and will pass successively through wire 81, contact 72, contact fingers 75 and 74, contact 71 and wire 79 to movable contact 66, then through stationary contact 65 and wire 78 to motor 33 and from motor 33 through wire 82 to negative main 84 thereby completing the electric circuit. Upon rotation of motor 33 as above described, the nut 31 will be driven so that the sleeve 30 carried by spindle 23 will be threaded upwardly therethrough whereby to effect the desired raising of runner 24.

When the spindle is raised to a predetermined position, the upper end 90 thereof is adapted to engage the forward end of lever 87 and to rock the same about its pivot as shown in Fig. 8 whereupon the knock-out bolt 89 engaging the rear end of lever 67 will rock the same about its pivot

so as to move the movable contact 66 out of engagement with stationary contact 65 and thus break the circuit through motor 33 and

automatically bring the upward movement of the spindle to a stop.

In bringing the runner downwardly the hand portion 85 of switch 70 is turned to a position where the indicator 86 is opposite the word "Down" and when so moved the contact fingers 74 and 75 of said switch will be brought to engage contacts 72 and 73 respectively. The electric current will then enter 10 through the positive main 83, and pass successively through wire 81, contact 72, contact fingers 74 and 75, contact 73 and wire 80 to motor 33 and from motor 33 through wire 82 to negative main 84 to complete the circuit. Upon this operation of the motor 33, the nut 31 will be rotated in the opposite direction to thread the sleeve 30 downwardly therethrough and thus effect the desired lowering of runner 24. During the lowering of 15 the spindle, it is necessary for the operator to hold the switch 70 in its "Down" position since the spring 77 tends to urge it normally to its "Off" position. This insures the grinding head stopping when the hand of the operator is removed from the switch. As the grinding head approaches the proper position with respect to the glass, the switch 70 may be turned off and on intermittently so as to provide a gradual lowering of the runner 20 into place. The grinding head moves upwardly and downwardly so slowly that there is practically no danger of it injuring the glass as it drops. When the spindle is lowered, the spring 69 will again return the contact 25 66 into engagement with contacts 65 and the weight of the forward end of lever 87 will cause it to again assume its normal position indicated in Fig. 9 so that the various parts of the apparatus will again be in position to permit the raising of the grinding runner.

It is to be understood that the form of the invention herewith shown and described is to be taken as the preferred embodiment of 45 the same, and that various changes in the shape, size and arrangement of parts may be resorted to without departing from the spirit of the invention or the scope of the subjoined claims.

50 We claim:

1. In combination in apparatus for surfacing glass, a vertical runner spindle, a grinding runner including a housing for receiving the lower end of the spindle therein, means for connecting the housing to the spindle in a manner to permit a bodily lowering movement of the runner relative to the spindle, as said runner wears away, and means carried by the housing for indicating to the operator the wear upon said runner.
2. In combination in apparatus for surfacing glass, a vertical runner spindle, a grinding runner including a housing for receiving the lower end of the spindle therein, 65 means for connecting the housing to the spin-

dle in a manner to permit a bodily lowering movement of the runner relative to the spindle, as said runner wears away, and cooperating stationary and movable means carried by the housing for indicating to the operator the wear upon said runner.

3. In combination in apparatus for surfacing glass, a vertical runner spindle, a grinding runner including a housing for receiving the lower end of the spindle therein, means for connecting the housing to the spindle in a manner to permit a bodily lowering movement of the runner relative to the spindle, as said runner wears away, and means carried by the housing for indicating to the operator the wear upon said runner, said means including a vertical member passing loosely through the top of said housing and normally maintained in a fixed position, and a second vertical member secured to the housing opposite the first member and adapted to move downwardly therewith.

4. In combination in apparatus for surfacing glass, a vertical runner spindle, a grinding runner including a housing for receiving the lower end of the spindle therein, a transverse pin carried by said spindle and projecting therebeyond at opposite ends thereof, the projecting end portions of said pin engaging said housing to effect rotation thereof and to also allow a bodily lowering movement of the runner relative to the spindle as said runner wears away, and means carried by the housing for indicating to the operator the wear upon said runner, said means including a vertical member passing loosely through the top of said housing and normally maintained in a fixed position, means acting to urge said member downwardly into engagement with one of the projecting end portions of said transverse pin, and a second vertical member secured to the housing opposite the first member and adapted to move downwardly therewith.

5. In combination in apparatus for surfacing glass, a vertical runner spindle, a grinding runner including a housing for receiving the lower end of the spindle therein, said housing being provided with opposed vertically elongated recesses, a transverse pin carried by said spindle and projecting therebeyond at opposite ends thereof, the projecting end portions of said pin being loosely received within said recesses to effect rotation of the housing and to also allow a bodily lowering movement of the runner relative to the spindle as said runner wears away, and means carried by the housing for indicating to the operator the wear upon said runner, said means including a vertical member passing loosely through the top of said housing and normally maintained in a fixed position, spring means within the housing acting to urge said member downwardly into engagement with one of the projecting end portions

of said transverse pin, and a second vertical member secured to the housing opposite the first member and adapted to move downwardly therewith.

5 Signed at Toledo, in the county of Lucas and State of Ohio, this 20th day of June, 1929.
